CLAIM

The ornamental design for a container in the shape of an onion, as shown and described.

DESCRIPTION

FIG. 1 is a top, rear, right side perspective view of a container in the shape of an onion showing my new design;

FIG. 2 is a right side elevation view thereof;

FIG. 3 is a rear elevation view thereof;

FIG. 4 is a front elevation view thereof;

FIG. 5 is a top plan view thereof; and,

FIG. 6 is a bottom plan view thereof.

The broken lines in the drawings illustrate the portions of the design that form no part of the claim.
